[57] CLAIM

The ornamental design for a home enema board kit, as shown and described.

DESCRIPTION

FIG. 1 is a perspective view of a home enema board kit showing my new design;

FIG. 2 is a right side elevational view thereof which is substantially equivalent to the left side elevational view;

FIG. 3 is a top plan view thereof;

FIG. 4 is a front end view thereof;

FIG. 5 is a rear end view thereof;

FIG. 6 is a bottom plan view thereof;

FIG. 7 is a cross-sectional view taken along the lines 7—7 of FIG. 1;

FIG. 8 is a cross-sectional view taken along the lines 8—8 of FIG. 1; and,

FIG. 9 is a cross-sectional view taken along the lines 9—9 of FIG. 1.

FIG. 4

FIG. 5

FIG. 6

FIG. 7

FIG. 8

FIG. 9
